Patented May 16, 1911.

UNITED STATES PATENT OFFICE.

ALLAN L. McGREGOR, OF CHICAGO, ILLINOIS.

AUTOMOBILE-BUFFER.

992,228.

Specification of Letters Patent. Patented May 16, 1911.

Application filed April 30, 1910. Serial No. 558,704.

To all whom it may concern:

Be it known that I, ALLAN L. McGREGOR, a citizen of the United States, residing at Chicago, in the county of Cook and State of Illinois, have invented certain new and useful Improvements in Automobile-Buffers, of which the following is a specification.

This invention relates to buffers intended for use on automobiles, and pertains more especially to that type wherein a horizontally disposed buffer-bar is elastically mounted upon and in advance of the forward ends of the usual side frame bars of the vehicle.

15 The invention has for its general object to provide an improved buffer of this type affording a more compact arrangement of the operating parts than heretofore, and better protection to the cushioning springs.

20 Another object of the invention is to provide an attachment to the frame bar which shall avoid the necessity of weakening the same through the formation of holes to engage fastening bolts.

25 My invention, its principle of operation, and the benefits and advantages secured thereby will be readily apparent to those skilled in the art from the following description taken in connection with the accompanying drawing, which shows one practical form in which the invention may be embodied, and in which—

30 Figure 1 is a top plan view of my improved automobile buffer showing also the forward ends of the usual side frame members on which the same is mounted. Fig. 2 is a side elevational view, in cross section through the buffer-bar and with the spring housing partly broken out to show the interior construction. Fig. 3 is a vertical section on the line 3—3 of Fig. 2, more particularly illustrating the means for securing the inner end of each buffer-bar supporting member to the side frame bar of the vehicle.

45 Fig. 4 is a sectional detail on the line 4—4 of Fig. 2.

50 Referring to the drawing, 5 designates the forwardly and downwardly projecting front ends of the usual side frame bars of the vehicle, herein shown as of inwardly facing channel form (Fig. 3). On the pivot bolts 6, which connect the extreme forward ends of the bars 5 to the upper ends of the usual semi-elliptic springs (not shown), are mounted a pair of buffer-bar supporting members 7, which are disposed substantially

horizontally and extend both forwardly and rearwardly of the pivots. The forwardly projecting portion of each supporting member is so formed as to provide a vertical 60 spring housing or chamber 8 and, directly behind the same, a pinion housing 9, the side walls of which are apertured to form bearings for a short rock-shaft. This latter, in the form shown in Fig. 4, is a composite 65 member and comprises a pair of axially bored shaft sections 10, each formed with inner polygonal portions 10^a and conical portions 10^b which are journaled in bearings 9^a in the side walls of the pinion housing 9; the two shaft sections being united endwise by a through-bolt 10^c. The outer ends of the rock-shafts thus formed have polygonal portions 10^d, mounted on which are a pair of upwardly and forwardly projecting arms 11 formed at their upper ends with split collars 12 adapted to clamp the buffer-bar 13 by means of clamp-bolts 14. Within the spring chambers 8 are housed strong compression springs 15 which abut 70 at their upper ends against the closed upper ends of the chambers 8. The lower end of each spring is directly engaged by a stress transmitting member in the form of a piston or plunger 16 that is made integral with 75 the lower end of a vertical slidable rack-bar 17 confined between the opposite side walls of the pinion chamber 9, which latter are integral with and merge into the cylindrical wall of the spring housing 8. Meshing with 80 the rack-bar 17 is a pinion segment 18 housed within the pinion chamber 9 and fast on the inner polygonal portions 10^a of the rock-shaft.

85 Integral with the spring housing 8 and projecting laterally therefrom is a lug 19 that forms a stop to limit the forward swing of the arm 11 through engagement with the lower edge of the latter. Preferably, and as herein shown, this stop is duplicated on 90 both sides of the spring chamber in order to make the latter interchangeable on both sides of the machine.

95 The inwardly projecting portion of the supporting member or arm 7 has a threaded aperture 20 at its inner end engaged by the threaded horizontal lower end 21 of an upwardly extending link 22 which is also formed with a threaded upper end 23. It is very desirable to avoid the weakening 100 of the side frame bar 5 which results from aperturing the same for the connection of

the link 22 thereto, and I have accordingly devised a simple and effective device through which the link 22 can be securely united to the side frame bar without involving any 5 drilling, cutting or weakening of the latter. This device, as herein shown, comprises a clamp which, by means of a single bolt, can be rigidly and securely united to the side frame bar, and a nut on the upper end of 10 the link 22 which is connected to said clamp. Fig. 3 illustrates principally the details of this device, wherein 24 designates one of the clamp members, which is formed with a horizontal surface 25 engaging the lower 15 side of the bar 5, and a vertical surface 26 engaging the outer vertical side of the bar 5; and 27 designates the other clamp member which has a horizontal surface 28 engaging the upper side of the lower horizontal flange 20 of the bar and a vertical surface 29 engaging the vertical edge of said lower horizontal flange. The clamp member 24 has a vertical aperture 30 for the passage of a clamp-bolt 31, and the two clamp-members are formed 25 with the opposed oppositely inclined wedge surfaces 32 and 33 engaged by a wedge 34 mounted on or formed integral with the bolt 31. It is obvious that as the bolt is drawn down by its nut 35, the wedge 34 acts to 30 force the clamp members 24 and 27, into intimate contact with the bar 5 at both their horizontal and vertical bearings thereon, so that the clamp is very securely held on said bar. On the threaded end 23 of the link 22 35 is a nut 36 which is formed with a vertical extension 37 that is apertured to receive a tap-bolt 38 that screws into a threaded hole 39 formed in the outer side of the clamp member 24.

40 The operation of the device will be readily apparent from the foregoing description. When the buffer-bar 13 encounters an obstacle offering sufficient resistance to call into play the cushioning springs, the said bar 45 swings on the arms 11 in an upward and rearward direction, this movement, through the rack and pinion mechanism and the stress-transmitting member 16 compressing the springs to an extent proportional to the 50 resistance offered by the obstacle. When the buffer-bar has been freed from engagement by the obstacle the reaction of the springs instantly restores it to normal position wherein the arms 11 engage stops 19. The 55 links 22 connecting the inner ends of the supporting arms 7 with the side frame bars 5 hold said arms rigid in any adjusted position determined by the engagement of the nuts 36 with the threaded upper ends of the 60 links 22. By disposing the cushioning springs vertically between the buffer-bar and the pivots of the carrying arms thereof, a compact construction is provided and one wherein the springs are well protected from 65 accidental injury or displacement.

Minor modifications and variations in the detail features of the device shown and described will readily occur to those skilled in the art, and are comprehended by the invention to the extent that they fall within the scope of the appended claims.

I claim:

1. In an automobile buffer, the combination of a buffer-bar, a cushioning spring, a spring abutment secured to forward end of 75 the vehicle, a rock-shaft, an arm fast on said rock-shaft and carrying said buffer-bar, a stress transmitting member directly engaging said spring, and rack-and-pinion connections between said stress transmitting member and said rock-shaft, substantially as described.

2. An automobile buffer, comprising in combination a buffer-bar, a pair of supporting members secured to the forward ends of 85 the side frame bars of the vehicle and forming shaft bearings and spring abutments, cushioning springs engaging said spring abutments, rock-shafts mounted in said bearings, arms fast on said rock-shaft and carrying said buffer-bar, stress transmitting members directly engaging said springs, and rack-and-pinion connections between said stress transmitting members and said rock-shafts, substantially as described. 95

3. An automobile buffer, comprising in combination a buffer-bar, a pair of supporting members secured to and projecting forwardly of the forward ends of the side frame bars of the vehicle, the forwardly 100 projecting portions of said supporting members being formed with shaft bearings and spring housings, cushioning springs in said housings, rock-shafts mounted in said bearings, a pair of arms each rigidly mounted 105 at one end on said rock-shafts and at its other end carrying said buffer-bar, stress transmitting members directly engaging said springs, slideable racks rigid with said stress transmitting members, and pinions fast on said rock-shafts and engaging said racks, substantially as described. 110

4. An automobile buffer, comprising in combination a buffer-bar, a pair of supporting members secured to and projecting forwardly of the forward ends of the side frame bars of the vehicle, the forwardly projecting portions of said supporting members being formed with spring housings at 115 their forward ends and shaft bearings in rear thereof, cushioning springs in said housings, rock-shafts mounted in said bearings, a pair of arms each rigidly mounted at one end on said rock-shafts and at its other end carrying said buffer-bar, stress transmitting members directly engaging said springs, slideable racks rigid with said stress transmitting members, pinions fast on said rock-shafts and meshing with said racks, and laterally projecting stops on said 120 125 130

spring housings engaging said arms and limiting the forward swing of said buffer-bar, substantially as described.

5. In an automobile buffer, the combination with a side-frame bar of the vehicle, of a buffer-bar supporting arm pivoted to the forward end of said side-frame bar and extending rearwardly thereof, an upwardly extending link connected to the rear end of 10 said arm and threaded at its upper end, and means for attaching the upper end of said link to said side-frame, bar comprising a clamp engaging said side-frame bar, a nut on the upper end of said link, and means 15 connecting said nut and clamp, substantially as described.

6. In an automobile buffer, the combination with a side-frame bar of the vehicle, of a buffer-bar supporting arm pivoted to

the forward end of said side-frame bar and 20 extending rearwardly thereof, an upwardly extending link connected to the rear end of said arm and threaded at its upper end, and means for attaching the upper end of said link to said side-frame bar comprising a 25 clamp formed by coöperating clamp-members both engaging vertical and horizontal sides of said side-frame bar and a wedge-bolt acting to draw said clamp members together vertically and horizontally on said side-frame bar, a nut on the upper end of said link, and a tap-screw connecting said nut and one of said clamp-members, substantially as described.
